UNITED STATES PATENT OFFICE.

JOHN F. BARKLEY, OF WILKINSBURG, PENNSYLVANIA.

INTAKE-FEEDER FOR SUCTION-CONVEYERS.

1,382,454.

Specification of Letters Patent. Patented June 21, 1921.

Application filed June 21, 1919. Serial No. 305,737.

To all whom it may concern:

Be it known that I, JOHN F. BARKLEY, a citizen of the United States, and resident of Wilkinsburg, in the county of Allegheny and State of Pennsylvania, have invented certain new and useful Improvements in Intake-Feeders for Suction-Conveyers, of which the following is a specification.

This invention is an intake feeder or valve 10 for controlling the feeding of material from a hopper to a pipe or conduit of a pneumatic conveyer.

In feeding loose materials, such as coke dust, ashes, coal, lime, etc., into the conveyer 15 pipe or conduit of a pneumatic suction conveyer, such loose materials have a tendency to arch over or bridge across the outlet opening of the hopper, and the prime object of the present invention is to prevent such 20 arching or bridging of the material, or at least to break the same down immediately upon the formation thereof, and thereby insure a supply of the material in a steady stream equal to or approximating the capacity of the conveyer.

In carrying out the invention the outlet from the hopper into the conveyer pipe is so disposed that should the material bridge across said opening, the inner or under side 30 of the bridge or arch will be subject to the cutting action of the air as it is drawn through a portion of the opening which is disposed in a plane at an angle to that portion of the opening over which the material 35 has bridged or arched, and therefore the bridge or arch will be quickly broken up and the feeding of the material will go on regularly and uninterruptedly.

In the drawings,

40 Figure 1 is a front elevation of a feeder of the present invention associated with the intake end of the conduit or pipe of a suction conveyer for loose materials;

Fig. 2 is a side elevation thereof;

45 Fig. 3 is an enlarged detail cross sectional view on the line 3—3 of Fig. 2;

Fig. 4 is a longitudinal sectional view on the line 4—4 of Fig. 3;

50 Fig. 5 is a detail perspective view of the gate or valve member of the present invention;

Figs. 6, 7 and 8 are views similar to Fig. 3 showing modified forms or shapes of the feed opening from the feed hopper to the 55 pipe or conduit of a suction conveyer.

In Fig. 2 of the drawings, 1 designates the

inlet end of a pipe or conduit of any common or preferred form of suction pneumatic conveyer system, said pipe having an open end for communication with the atmosphere and preferably provided with an external annular flange 2 with which the intake feeder of the present invention may be connected.

In the present embodiment of the invention, there is provided a hopper 3 which is open at its upper end for the introduction therethrough of the loose material to be fed to the conveyer pipe. Access to the interior of the hopper may be conveniently had 60 through a suitable door 4 provided in one upright side of the hopper. The bottom 5 of the hopper is provided with an outlet opening 6 extending throughout said bottom from the front to the rear thereof, and aligned

openings and notches 7 and 8 are provided in the rear and front walls respectively of the hopper above and in communication with the feed opening 6. Below the bottom 5 of the hopper there is a pipe section 9 open at 75 opposite ends and provided at its rear or inner end with an external flange 10 lying against the flange 2 and secured thereto by means of suitable fastenings 11, thus forming an inlet chamber through which air and 80 the material conveyed by the air may enter the pipe 1. The bottom 5 of the hopper separates the hopper from the pipe section 9, and the opening 6 provides a communication from the interior of the hopper to the 85 pipe section 9. As best indicated in Fig. 4, it will be seen that the opening 7 communicates with the inlet end of the conveyer pipe 1, so that there is communication directly from the hopper 3 through the opening 7 into the pipe 1, as well as an indirect communication from the hopper through the opening 6 into the pipe section or inlet chamber 9 and thence into the pipe 1.

95 For controlling communication between the hopper and the suction pipe 1, there is provided a valve or gate, one embodiment of which has been shown in Figs. 1 to 5, inclusive, wherein it will be seen that said valve or gate 12 is of inverted substantially 100 V-shape, and is provided at each of its bottom edges with an outstanding longitudinal flange 13, and at one end with a handle 14, preferably in the form of a bail or yoke having its extremities riveted or otherwise 110 secured to the adjacent ends of the respective flanges 13, as indicated at 15. The gate

or valve lies within the opening 6 and projects upwardly into the hopper 3. The flanges 13 are mounted to slide in suitable guideways. As shown in Fig. 3 of the drawings, it will be seen that each guideway is defined by a plate or bar 16 secured to the under side of the bottom 5 of the hopper and spaced from said bottom, which bottom constitutes the top of the guideway. The 10 gate or valve is of a length to lie in the openings 7 and 8 so as to close the same and also close the opening 6 when it is desired to shut off communication between the hopper 3 and the pipe line 1. By pulling 15 the gate or valve outwardly, to a position as shown in Fig. 4, it will be seen that the contents of the hopper may pass through the opening 7 into the pipe line 1 as well as downwardly through the opening 6, into 20 the pipe section 9 and thence into the pipe line 1, under the suction action which is established in the pipe line 1, the front end of the pipe section 9 being open to the atmosphere as hereinbefore described. With 25 the valve or gate in any open position, should the loose material in the hopper bridge or arch over the opening 6, the air which is sucked in through the pipe section 9 and thence through the opening 7 into 30 the pipe line 1, has a cutting action on the inner or under side of the bridged or arched material, whereby said bridge or arch will be cut down and further building up of the arch or bridge prevented, whereby a 35 continuous flow of material from the hopper into the pipe line is assured, substantially equal to the capacity of the pipe line. When the valve or gate is pushed inwardly until its inner end occupies the opening 7, all 40 communication is cut off from the hopper to the pipe line 1.

Instead of having the inverted substantially V-shaped form of valve or gate, the gate may have different cross-sectional shapes, some of which are shown in Figs. 45 6, 7 and 8, and designated, respectively, 12^a, 12^b, and 12^c, the openings in the rear wall of the hopper of course conforming to the cross-sectional shape of the gate or valve 50 employed.

It will here be explained that the gate or valve is semi-tubular in form with its lower side open and in communication with the suction nozzle formed by the pipe section 55 9, whereby a current of air will be directed by this semi-tubular gate or valve against the inner or under side of the bridged or arched material which may form across the opening 6 between the inner end of the valve 60 or gate and the rear wall of the hopper.

What I claim is:

1. In a pneumatic conveyer, the combina-

tion with a suction conduit, of a feed hopper connected to one end of said conduit, said hopper having side and bottom walls, said 65 bottom wall being cut away throughout its length from front to rear thereof, and the rear and front side walls being notched upwardly from said cut-away portion forming a continuous outlet opening, and an arched 70 valve member controlling said outlet opening.

2. In a pneumatic conveyer, the combination with a suction conduit, of a feed hopper connected to one end of said conduit, said 75 hopper having side and bottom walls, and an inlet chamber below said bottom wall, said bottom wall being cut away throughout its length from front to rear thereof, and the rear and front side walls being notched 80 upwardly from said cut-away portion forming a continuous outlet opening, and an arched valve slidably mounted within the hopper and controlling said outlet opening, 85 said valve working through the notch in said front wall.

3. In a pneumatic conveyer, the combination with a suction conduit, of a feed hopper connected to one end of said conduit, said hopper having side walls, a bottom wall, 90 and an inlet chamber below said bottom wall, said side walls and said bottom wall being cut away forming a continuous opening communicating with said conduit, and adjustable means for bridging said opening. 95

4. In a pneumatic conveyer, the combination with a suction conduit, of a feed hopper connected to one end of said suction conduit, said hopper having side walls, a bottom wall, and an inlet chamber below said 100 bottom wall, said side walls and said bottom wall being cut away forming a continuous opening communicating with both said suction conduit and said inlet chamber, and means for bridging said opening, said 105 means being slidable along said opening to regulate and control the size of said opening.

5. In a pneumatic conveyer, the combination with a suction conduit, of a feed hopper connected to one end of said suction conduit, said hopper having side walls, a bottom wall, and an inlet chamber below said 110 bottom walls, said side walls and said bottom wall being cut away forming a continuous opening communicating with both said suction conduit and said inlet chamber, and a valve arching over and slidable along said opening, said valve having flanges, and said bottom wall having guideways 115 120 slidably receiving the flanges on said valve.

In testimony whereof I have hereunto set my hand.

JOHN F. BARKLEY.
